AUTOMATIC RELEASE AND RESET SYSTEM

William Ieu-Liang Wu, New York, N. Y., assignor
to the United States of America as represented
by the Secretary of the Navy

Application July 4, 1944, Serial No. 543,494

6 Claims. (Cl. 250—27)

1

This invention relates to automatic release systems, and more particularly to systems in which automatic means are provided for operating a release device in response to input signals having particular characteristics.

In general, automatic release systems or trippers are used to actuate switching circuits or to control the operation of various mechanisms in response to input signals derived from some device with which they are associated. Such tripper systems ordinarily include discriminating means such that they will operate only in response to signals having certain chosen characteristics. Signal characteristics usually chosen for discrimination are peak amplitude and predominant frequency component. Thus, in some trippers, the release device is actuated whenever the input signal reaches a peak value greater than a predetermined threshold. In such devices, tripping occurs whenever the threshold is exceeded irrespective of the frequency of the input signal. Unsatisfactory operation may therefore result due to tripping in response to spurious signals or "noise" such as high- or low-frequency pulses derived from sources other than the control device and having amplitudes in excess of the chosen threshold. Furthermore, when signals of widely varying amplitudes are received, the threshold value will be exceeded at varying intervals before the occurrence of the peak signal, thus introducing further inaccuracies.

It is an object of this invention, therefore, to provide an automatic release system which will not trip on signals having characteristics other than those chosen to actuate the device even though the amplitude of such undesired signals exceeds the chosen amplitude by appreciable amounts.

In view of the above, the present invention provides in one aspect an automatic release circuit arranged to operate in response to input signals of a chosen type, a release device, and means for actuating this device only when an input signal of the chosen type is received, these circuits including at least two differentiating circuits having time constants differing by an amount such that the difference in amplitudes of the differentiated output potentials in response to the same input signal is appreciable only when the input signal is of the chosen type, and means for adding these differentiated potentials algebraically and applying the resultant potential to the release device.

In one embodiment of the invention, the automatic release system is used to govern the operation of a release device comprising a relay controlled by an arc-discharge tube. It will be un-

2

derstood, however, that the release system may be used for the control of any other suitable release device.

The above and other features of the invention will be described in detail in the following specification and pointed out in the claims.

In the drawings:

Fig. 1 is a circuit diagram of an automatic release system according to the invention; and

Fig. 2, 3 and 4 are reproductions of oscillograms showing potentials existing at various points of the circuit of Fig. 1.

The system illustrated in Fig. 1 of the drawings is arranged for operation in response to two-sided input signals such as, for example, those appearing at the output of a push-pull amplifier. Thus, input terminals 10 and 12 are provided from which a two-sided signal may be applied through coupling capacitors 14, series resistors 16, potentiometers 18 and protective resistors 20 to the grids of a push-pull class A amplifier stage comprising vacuum tubes 22 and 24. As indicated in Fig. 1, potentiometers 18 are linked together mechanically and control the signal potentials, in respect to ground, applied to the grids of amplifier tubes 22 and 24. The setting of these potentiometers determines the threshold or minimum amplitude of input signal for which tripping will occur. Preferably, the input circuits to vacuum tubes 22 and 24 are designed so that they have a relatively high time constant irrespective of the setting of potentiometers 18, thus preventing undesirable distortion of the input signal.

The cathodes of amplifier tubes 22 and 24 are connected through a common resistor 26 to ground, while the plates are connected through load resistors 28 to a source of positive potential indicated by B⁺. In addition, each plate is bypassed to ground by a capacitor 30, these capacitors acting in conjunction with the dynamic plate resistances of the vacuum tubes to produce filtering action which tends to discriminate against any very high-frequency components present in the input signal.

The plates of vacuum tubes 22 and 24 are coupled through capacitors 32 to the grids of vacuum tubes 34 and 36 which are operated as a cathode-follower stage. Thus the plates of these vacuum tubes are connected together and to the source of positive potential indicated by B⁺, and the grids are connected through resistors 38 to ground. The cathodes of these tubes are connected to the fixed contacts of a two-pole, three-position switch 40, in such a manner that either cathode or both cathodes may be connected through resistor 42 to the junction of resistors 44 and 46, which are connected in series as a volt-

age divider between the source of positive potential at B^+ and ground.

The positive potential applied to the cathodes of vacuum tubes 34 and 36 is such that each of the tubes is biased beyond cutoff and operates as a rectifier, conducting only when a positive signal appears at its grid. In addition, since these tubes operate as cathode followers, their output has a low internal impedance. Thus the voltage applied to the circuits following this stage will be substantially independent of the loading due to such circuits.

Since the signals applied to the grids of vacuum tubes 34 and 36 have opposite polarities at all times, it will be understood that, by means of switch 40, control-signal peaks of either polarity may be transmitted to the remaining circuits of the release system. Depending upon the setting of this switch, the system may be made to trip on the positive peak, on the negative peak, or on the first peak received whether it be positive or negative. In the following description it is assumed that the common cathode connection corresponding to the last-mentioned condition is used. Thus a positive pulse, having the same form as the first pulse received, whether it be positive or negative, is applied to the remaining portions of the release system.

The positive pulse just referred to is applied simultaneously to two differentiating networks which together operate as a frequency-discriminatory circuit. These networks comprise respectively capacitor 43 and resistor 45, and capacitor 48 and resistor 50. Preferably, capacitor 43 has a capacitance differing from that of capacitor 48 by an amount determined by the type of signal chosen to operate the release system, while resistors 45 and 50 have the same resistance. Resistors 45 and 50 are connected together and to the junction of voltage-divider resistors 52 and 54 connected between the source of positive potential at B^+ , and ground.

Capacitors 43 and 48 are so chosen that for input-signal components or noise of very high frequency, each offers negligible reactance. The potentials appearing across resistors 45 and 50 are, therefore, substantially equal and their difference is very small. On the other hand, when the input signal has components of very low frequency, the reactance of either of the capacitors is so high that negligible potentials appear across resistors 45 and 50. When, however, the input signal possesses the desired frequency characteristics, each of the capacitors taken in conjunction with its series resistor tends to differentiate the signal. The two derivative outputs now have different amplitudes due to the fact that the two differentiating circuits have different time constants.

The outputs of the two differentiating circuits are applied through series resistors 56 to the grids of a two-sided cathode-follower stage comprising vacuum tubes 58 and 60. The cathodes of vacuum tubes 58 and 60 are connected through cathode resistors 62 to ground, while the plates of these tubes are connected together and to the source of positive potential at B^+ . Thus it will be understood that the positive potential appearing at the junction of resistors 52 and 54 is applied to the grids of vacuum tubes 58 and 60. Preferably this potential is relatively high and serves to raise the static plate current of these vacuum tubes to such a value that they will operate on a linear portion of their plate current-grid voltage transfer characteristic. This reduces

the possibility that the two tubes will introduce faulty operation due to mismatching and, in addition, gives them the high mutual conductance necessary to cause them to operate as cathode followers.

Due to their differentiating action, the frequency-discriminatory circuits above described have outputs including both positive and negative pulses. The negative portions of these outputs are clipped by means of diodes 63 and 64, the cathodes of which are connected to the grids of tubes 58 and 60, respectively, while the diode plates are connected together and to the junction of resistors 45 and 50. Whenever the signal output of the differentiating circuits becomes negative, the diodes become conducting and act to bypass the negative portions of the signals. Positive pulses are not affected by the diodes and are, therefore, applied to the grids of the succeeding stage.

The cathodes of tubes 58 and 60 are connected through coupling capacitors 66 and 68 to a peak-tripping stage comprising diodes 70 and 72 and associated circuits. The plate of diode 70 is thus connected to capacitor 66 and through resistor 74 and bias battery 76 to ground, while the plate of diode 72 is connected to capacitor 68 and through resistor 78 to ground. The cathode of diode 70 is connected through battery 76 to ground, while that of diode 72 is connected directly to ground. The plates of diodes 70 and 72 are also connected through series resistors 80 to the grid and cathode, respectively, of a grid-controlled arc-discharge tube 82 such as, for example, a thyratron. Capacitor 84 is connected between the cathode and grid of discharge tube 82, and serves to filter out high-frequency disturbances associated with the signal applied between these points.

Considering now the action of the peak-tripping circuits comprising diodes 70 and 72, together with their input circuits including respectively capacitor 66 and resistor 74 and capacitor 68 and resistor 78, it will be seen that, so long as the potentials at the cathodes of vacuum tubes 58 and 60 are increasing, the plates of diodes 70 and 72 will be driven positive, thereby rendering them conductive and hence allowing coupling capacitors 66 and 68 to charge through the diodes. When the peak of the signal is reached, however, and the potentials at the cathodes of vacuum tubes 58 and 60 begin to fall, conduction through diodes 70 and 72 stops, and capacitors 66 and 68 discharge through resistors 74 and 78, respectively. The negative potentials thus applied at the plates of diodes 70 and 72 are in turn applied to the grid and cathode, respectively, of arc discharge tube 82.

The plate of discharge tube 82 is connected through series resistor 85 and contacts 86 of relay 87 to the source of positive potential at B^+ , and its shield grid is connected to its cathode. In addition, the cathode of this tube is connected to the plate of diode 88, the cathode of which is connected through series resistor 90 to the junction of voltage-divider resistors 92 and 94 connected in series between the source of positive potential at B^+ and ground. Thus, so long as discharge tube 82 is not conducting, its cathode is isolated from the remaining portions of the tripping circuits. This prevents application of the potential at the plate of diode 72 to succeeding stages and thus prevents unbalancing of the peak-tripping stage. The positive potential at the junction of resistors 92 and 94 biases the diode

and prevents the flow of residual current therethrough.

It will be recognized that due to the action of bias battery 76, which normally maintains the grid of the discharge tube at a negative potential with respect to its cathode, the discharge tube will not fire until its grid is made somewhat less negative in respect to the cathode. However, due to the difference in amplitudes of the differentiated signals at the plates of diodes 70 and 72, the negative potential applied to the cathode of the discharge tube is somewhat greater than that applied to the grid thereof whenever the input signal to the release system is of the chosen type. The net result is then to reduce the grid bias by the algebraic sum of these two potentials. If the difference in amplitudes of the differentiated signals resulting from the input signal from the tripper system as limited by threshold potentiometers 18 is sufficient to overcome the normal negative bias on discharge tube 82, therefore, this tube fires.

The cathode of diode 88 is also connected through rheostat 96 and delay capacitor 98 to ground. A voltage-regulator tube 100 is connected in series with protective resistor 102, delaying resistor 104 and bias battery 106 across delay capacitor 98. The cathode of voltage-regulator tube 100 is also connected through resistor 108 to the grid of control tube 110, the cathode of which is connected through cathode resistor 112 to ground. Thus it will be seen that battery 106 supplies bias voltage to this tube. The plate of control tube 110 is connected through coil 113 of relay 87 to the source of positive potential at B+, so that the flow of current through this tube causes operation of the relay which is provided with control-circuit contacts 114, to which may be connected a device to be controlled by the release system. Preferably, the bias voltage supplied by battery 106 to control tube 110 is sufficient to cut off the tube thereby to prevent the flow of residual current therethrough. Such residual current would otherwise flow through the coil of relay 87 and render the release action of the relay more sluggish.

So long as discharge tube 82 is not conducting, its cathode is isolated by diode 88 as explained above. Once the discharge tube fires, however, its cathode and therefore the plate of diode 88 become positive, thereby causing diode 88 to conduct. This allows capacitor 98 to charge through rheostat 96, the rate of charge being determined by the amount of resistance offered by the rheostat. After a time determined by the time constant of the RC circuit formed by rheostat 96 and capacitor 98, the potential across capacitor 98 reaches the break-down potential of voltage-regulator tube 100, and this tube breaks down, thereby transferring the charge from capacitor 98 to delay capacitor 109 connected between the cathode of voltage-regulator tube 100 and ground. The potential across the latter capacitor is applied to the grid of control tube 110 and causes it to conduct thereby tripping relay 87, opening contacts 86, and closing contacts 114. The opening of contacts 86 extinguishes discharge tube 82 by removing the plate potential therefrom, while the closing of contacts 114 establishes the circuit of the device to be controlled. The charge of capacitor 109 leaks off slowly through delaying resistor 104 to ground, and eventually lowers the grid potential of tube 110 to such a value that the relay returns to its normal position, opening the controlled circuit and rees-

tablishing the circuit to the plate of the discharge tube. The time constant of the circuit comprising capacitor 109 and resistor 104 is so chosen that the difference in potential between the grid and the cathode of discharge tube 82 will have returned to such a value before the plate voltage is reapplied to that tube that the tube does not again become conducting. At the end of the cycle of operations just described, the tripper circuit is thus reset for another cycle.

For a better understanding of the operation of the above-described circuits, reference is made to Figs. 2, 3 and 4 of the drawings. These figures are oscilloscograms, taken on a common time base, showing the variations in potentials at various points in the circuits.

In Fig. 2, the solid trace indicates the form of a typical input signal of a particular type in response to which the device of the invention may be arranged to operate. This signal is amplified in vacuum tubes 22 and 24 and is applied to the grids of the rectifier stage comprising cathode-follower tubes 34 and 36. Assuming that switch 40 is set for the common cathode connection mentioned above, both positive and negative peaks will appear as positive pulses at the common connection to the differentiating circuits. The shape of the signal at this point is indicated by the dashed trace in Fig. 2.

The differentiating circuits operate simultaneously on this signal and the negative portions of the differentiated output signals from these circuits are clipped by diodes 63 and 64. The two signals applied to the grids of vacuum tubes 58 and 60 are shown in Fig. 3, the solid trace indicating the signal at the grid of tube 58 and the dashed trace indicating that at the grid of tube 60. It will be noted that, due to the differing time constants of the differentiating circuits, the signals applied to the grids of vacuum tubes 58 and 60 differ appreciably in amplitude.

These signals are introduced to the peak-tripping stage which operates upon them in the manner already described. The signals applied to the discharge tube are then as indicated in Fig. 4, in which the solid trace represents the signal at the grid of the discharge tube and the dashed trace the signal at the cathode of the same tube, each with respect to ground.

If the difference between the potentials at grid and cathode of the discharge tube is such that the bias on that tube due to battery 76 is overcome, this tube fires and the remaining circuits operate as already described ultimately to close relay 87.

While the vacuum tubes used in the tripper system of the invention may be of various types and the magnitudes of the circuit components used depend to a large extent upon the type of signal chosen to operate the system and may, in general, vary between wide limits, the following were used in one successful embodiment of the invention: Vacuum tubes 22 and 24 each formed one half of a type 12SL7 tube. Likewise, each of vacuum tubes 34 and 36 formed one half of a type 12SL7 tube. Each of diodes 63 and 64 formed one half of a type 6H6 tube as did each of diodes 70 and 72. Each of vacuum tubes 58 and 60 formed one half of a type 12SL7 tube, and discharge tube 82 was a type 2050 tube. The voltage regulator tube 100 was a type VR-75 tube, while diode 88 formed one half of a type 12SL7 tube having its grid and plate joined together, and vacuum tube 110 formed the other half of the same type 12SL7 tube.

Other circuit components had the following values:

Resistors 38, 104	megohms	5.1
Resistors 16	do	1.8
Resistors 45, 46, 50, 56, 74, 78, 94, 108	do	1.0
Resistors 20	do	0.5
Resistors 28, 62	do	0.25
Resistors 80	do	0.2
Resistor 90	do	0.1
Resistor 54	ohms	50,000
Resistor 44	do	40,000
Resistor 52	do	25,000
Resistor 92 and rheostat 96	do	10,000
Resistor 85	do	7500
Resistor 102	do	3000
Resistor 112	do	2000
Resistor 26	do	1500
Potentiometers 18	megohms	1.25
Capacitors 14, 32, 98	microfarads	2.0
Capacitors 30	do	0.1
Capacitor 43	do	0.25
Capacitors 48, 66, 68, 109	do	0.5
Capacitor 84	do	0.001

Batteries 76 and 106 each had a rating of 6 volts and the source of positive potential at B⁺ was 300 volts.

Using the above circuit components, the two differentiating circuits had time constants of 0.25 and 0.5 second, respectively. With these time constants signals having predominant frequencies lying between 0.1 cycle per second and 10 cycles per second were effective to operate the tripper, while signals having other predominant frequencies and much greater amplitudes were discriminated against and did not operate the tripping circuits.

Having thus described my invention, what I claim is:

1. In a discriminating circuit arranged to operate in response to input signals of a chosen minimum peak amplitude and a chosen frequency range, means for actuating a load only when an input signal of the chosen characteristics is received, said means including at least two differentiating circuits having time constants differing by an amount such that the difference in amplitudes of the differentiated output potentials in response to the same input signal is appreciable only when the input signal is of the chosen characteristics, and means for adding said differentiated potentials algebraically and applying the resultant potential to the load.

2. In a discriminating circuit arranged to operate in response to input signals of a chosen minimum peak amplitude and a chosen frequency range, a grid-controlled arc-discharge tube for controlling a load, circuits for controlling the potential at the grid of said tube to render it conductive only when an input signal of the chosen characteristics is received, said circuits including at least two differentiating circuits having time constants differing by an amount such that the difference in amplitudes of the differentiated output potentials in response to the same input signal is appreciable only when the input signal is of the chosen characteristics, and means for adding said differentiated potentials algebraically and applying the resultant potential to the grid of said discharge tube.

3. In a discriminating circuit arranged to operate in response to input signals of a chosen minimum peak amplitude and a chosen frequency range, means for actuating a load only when an input signal of the chosen characteristics is re-

ceived, said means including amplifying and rectifying stages and at least two differentiating circuits having time constants differing by an amount such that the difference in amplitudes of the differentiated output potentials in response to the same input signal is appreciable only when the input signal is of the chosen characteristics, and means for applying the difference potential to the load.

4. In a discriminating circuit arranged to operate in response to input signals of a chosen minimum peak amplitude and a chosen frequency range, means for actuating a load only when an input signal of the chosen characteristics is received, said means including a polarity-selecting rectifying stage and at least two differentiating circuits having time constants differing by an amount such that the difference in amplitudes of the differentiated output potentials in response to the same input signal is appreciable only when the input signal is of the chosen characteristics, and means for adding said differentiated potentials algebraically and applying the resultant potential to the load.

5. In a discriminating circuit arranged to operate in response to input signals of a chosen minimum peak amplitude and a chosen frequency range, a grid-controlled arc-discharge tube for controlling a load, circuits for controlling the potential at the grid of said tube to render it conductive only when an input signal of the chosen characteristics is received, said circuits including amplifying and rectifying stages and at least two differentiating circuits having time constants differing by an amount such that the difference in amplitudes of the differentiated output potentials in response to the same input signal is appreciable only when the input signal is of the chosen characteristics, and means for adding said differentiated potentials algebraically and applying the resultant potential to the grid of said discharge tube.

6. In a discriminating circuit arranged to operate in response to input signals of a chosen minimum peak amplitude and a chosen frequency range, a grid-controlled arc-discharge tube for controlling a load, circuits for controlling the potential at the grid of said tube to render it conductive only when an input signal of the chosen characteristics is received, said circuits including a polarity-selecting rectifying stage and at least two differentiating circuits having time constants differing by an amount such that the difference in amplitudes of the differentiated output potentials in response to the same input signal is appreciable only when the input signal is of the chosen characteristics, and means applying the difference potential to the grid of said discharge tube.
